UNITED STATES PATENT OFFICE.

OVERTON SACKSTEDER, JR., OF MUNCIE, INDIANA, ASSIGNOR TO ALADDIN MANUFACTURING COMPANY, OF MUNCIE, INDIANA, A CORPORATION.

DESIGN FOR A PORTABLE LAMP.

Application filed August 30, 1927. Serial No. 23,248. Term of patent 14 years.

To all whom it may concern:

Be it known that I, OVERTON SACKSTEDER, Jr., a citizen of the United States, residing at Muncie, in the county of Delaware and State of Indiana, have invented a new, original, and ornamental Design for Portable Lamps, of which the following is a specification, reference being had to the accompanying drawing, forming a part hereof.

I claim—

The ornamental design for a portable lamp as shown.

OVERTON SACKSTEDER, JR.
